UNITED STATES PATENT OFFICE.

MARTIN M. WILSON, OF HONEY GROVE, TEXAS.

WATER HEATER AND PURIFIER.

SPECIFICATION forming part of Letters Patent No. 352,638, dated November 16, 1886.

Application filed March 24, 1886. Serial No. 196,401. (No model.)

To all whom it may concern:

Be it known that I, MARTIN M. WILSON, of Honey Grove, in the county of Fannin and State of Texas, have invented a new and useful Improvement in Water Heaters, Purifiers, and Condensers, which improvement is fully set forth in the following specification and accompanying drawings, in which—

Figure 1 is a longitudinal vertical central section of my improved heater and purifier; Fig. 2, a perspective view, with the top and side partly cut away; and Fig. 3, a perspective view of the corrugated plate detached.

This invention relates to an improvement in heaters, condensers, and purifiers so constructed and arranged that the water as it enters the condenser or purifier comes at once in contact with the exhaust-steam, which contact partially condenses the steam, and at the same time heats or decomposes and changes the composition of the water, causing it to give up and deposit the greater portion of the mineral matter it contains. The remainder of the steam passes over the surface of the water in the closed part. The water passes through the bottom of the partition into a second apartment, where it is at rest, the oil and grease passing off from an overflow-pipe. Thus the greater part of the sediment and mineral matter is deposited in the first apartment, while the remainder is permitted to settle in the second, where the water is comparatively still. The water is then in a fit condition to be drawn off and used again in the boiler. As this water is now quite pure, there will be great saving in trouble and time in cleansing the boiler, and incidentally, as the boiler is thus kept quite clean, economizing the use of fuel and water, all of which will now be fully set forth in detail.

In the accompanying drawings, A represents the external casing of an ordinary condenser-tank. This has an exhaust-steam pipe, B, connected at its forward end, and a fresh-water pipe, C, also connected therewith immediately above the exhaust-pipe B. The end of the tank containing these pipes B and C is provided with a cover, D, as shown in the drawings, extending midway of the tank, the opposite end being preferably uncovered. An

exhaust-water pipe, E, is provided at this end of the tank for the purpose of drawing off the water and pumping it back into the boiler while being purified, while the opposite side of this end of the tank is also provided with a small overflow-pipe, F, for the purpose of permitting the grease and oil being removed from the tank. Midway the tank is provided with a vertical partition, G, shutting off the end of the first compartment, H. The bottom of this partition G is provided with suitable openings, I, through which the water passes from the apartment H into the uncovered apartment J. The apartment H is provided centrally with a partition, K, extending from the bottom to about midway the height of the tank, having its entire surface formed with perforations L.

Immediately beneath the cold-water pipe C, I provide a corrugated convexed disk, M, secured beneath the cover D, and immediately over the opening of the exhaust-pipe, so that when the fresh water enters the tank H through the pipe C it will strike the upper or convexed corrugated face of the said disk M, when it is sprayed or deflected in small particles, and as the exhaust-steam enters the compartment H through the pipe B the sprayed water, coming in contact with the steam, condenses a considerable amount of the steam, and at the same time heats, decomposes, or changes the composition of the water, causing it to give up or deposit the greater portion of the mineral matter it contains, the steam passing over the surface of the water increasing the heat, and decomposition still further condenses the steam, until the remainder passes out at the large pipe N, through the cover D, at the opposite end of the compartment H from the pipes B and C.

The partition K separates the larger particles from the water, causing it to settle in the bottom of the compartment H, immediately beneath the disk M. Additional matter is deposited on the side of this partition K. The water passing out through the opening I in the partition G enters the compartment J, where it is not agitated. The remainder of the fine matter and sediment is permitted to settle, and the oil and grease is drawn off

through the overflow-pipe F, and the water drawn off as fast as desired through the pipe E, and returned to the boiler.

Having described my invention, what I claim is—

1. In the condenser A, having the cover D, the water-pipe C and exhaust-steam pipe B, combined with the corrugated convex disk M, whereby the water falls upon the disk and the steam enters beneath it, substantially as described.
2. The condenser A, having water-apartments H and J and cover D, with water and escape pipes C and N passing through it, said apartment J divided by the perforated partition K, and the corrugated disk M and ex-

haust-steam pipe B, in the combination shown and described.

3. In a condenser, and in combination with the water-apartment H, provided with water and exhaust-steam inlets N and a spraying and condensing disk, the apartment J, and the partition G, having aperture I at its base and the escape-pipes E and F, respectively, at the bottom and sides, substantially as described. 25

In testimony that I claim the foregoing I have hereunto set my hand, this 11th day of February, 1866, in the presence of witnesses.

M. M. WILSON.
